(No Model.)

S. B. LUCE.

DEAD EYE.

No. 290,993.

Patented Dec. 25, 1883.

FIG. 2.

FIG. 1.

FIG. 3.

The diagram shows a circular component with a central hole labeled 'A'. The outer edge is hatched with diagonal lines. A flared base is labeled 'B'. The flared base has a circular feature labeled 'C' with a cross-hatched pattern. The label 'G' is positioned to the right of the base.

This technical cross-sectional diagram illustrates a mechanical assembly, possibly a pump or valve. The diagram features a central vertical axis with various components labeled A through F. Labels A and B are positioned on the left side, while C, D, E, and F are on the right. The central area contains a label 'G' above a heart-shaped component. The entire assembly is rendered with fine hatching lines to indicate different parts and materials.

A cross-sectional diagram of a dental arch, labeled 'A' at the top left. The arch is U-shaped with a central circular opening. The base of the arch is labeled 'C' at the bottom right. The diagram shows a vertical line of hatching through the arch, and a horizontal line of hatching through the central opening.

UNITED STATES PATENT OFFICE.

STEPHEN B. LUCE, OF NEWPORT, RHODE ISLAND.

DEAD-EYE.

SPECIFICATION forming part of Letters Patent No. 290,993, dated December 25, 1883.

Application filed May 19, 1883. (No model.)

To all whom it may concern:

Be it known that I, STEPHEN B. LUCE, of Newport, in the county of Newport and State of Rhode Island, have invented certain new and useful Improvements in Dead-Eyes, of which the following is a full, clear, and exact description.

As well known, for the setting up of ship's rigging, two dead-eyes, or substitutes therefor, are usually employed, the one attached to the rigging to be set up, and the other to a suitable fixture on the side or the deck of the ship. The two dead-eyes are connected by a setting-up rope or lanyard, which is rove from one to the other thereof, and one end of the rope is secured in any suitable manner to one of the dead-eyes and the other end is left free to be fastened to and unfastened from any suitable fixture of the ship or to the other dead-eye, so as to be capable of being manipulated to set up the ship's rigging as desired, and when such setting up is completed to be made fast and secure.

This invention relates to a dead-eye for such use and purpose; and it consists of a dead-eye made of metal or other suitable material, and constructed with a series of external and parallel peripheral grooves of a construction and arrangement to receive a coil or doubling of the setting-up rope or line, and keep such coil or doubling, and thus leave them free for movement through and along said grooves without interference between and friction of one coil upon another, in combination with an ear-piece joined by a cross pin or bolt, or with other device or devices of suitable construction, not only to keep the rope rove through the dead-eye, as aforesaid, from slipping laterally off the same, but also to connect the dead-eye either to the ship's rigging or to the deck, or other suitable fixture of the ship, according as the dead-eye is used at either one or the other end of the setting-up rope for the dead-eyes to swing on such connections, all substantially as hereinafter described.

In the accompanying plate of drawings the present improved dead-eye is illustrated, Figure 1. being a vertical section of two of the same connected by the setting-up rope, and showing one as secured in position to the side or deck of the ship and the other to the shroud.

Fig. 2 is an edge view of the eye of Fig. 1, which is shown as secured in position; Fig. 3, an edge view of the dead-eyes of Fig. 1, with the setting-up rope removed; Fig. 4, a face or side view, enlarged, of the dead-eye shown in Fig. 2; Fig. 5, an edge view of Fig. 4, but showing a part in central vertical section; Fig. 6, a face or side view similar to Fig. 4, but showing modification.

In the drawings, A represents a dead-eye. This dead-eye is made of metal or of other suitable material, preferably of metal, and it has a series of parallel grooves, a, each of which partially surrounds its external periphery, B, extending, however, at least one-half of said periphery, if not more, and of a sufficient depth, and with sufficient separation to keep the coils or doublings of the setting-up rope which are in them apart and out of contact with each other, and for the said several coils of the rope to have free movement through and along said groove without interference between and friction of one coil upon another.

C are two ear-pieces projecting beyond the grooved periphery B of the dead-eye at each side or face thereof, joined by a cross bolt or pin, D, fastened against escape in any suitable manner—as, for instance, by means of a head, E, at one end and a cross-pin, F, 80 driven through the bolt D at the other end, each outside of the ear-pieces.

G is a staple or pin, having an eye, b, by which it is swiveled or hung upon the cross-bolt and swung thereon between inside faces 85 of the ear-pieces. This staple or pin is fastened in any suitable manner to the side or deck or other suitable fixture of the ship, and thus one dead-eye being secured in place, the other dead-eye is attached, by its pin in the 90 usual manner, to the ship's rigging or shroud K through its thimble L, as shown in Fig. 2, and thus, with the setting-up rope running from one dead-eye to the other, and doubled or coiled partially about and within the grooves 95 a of each of said dead-eyes, as has been described, and said rope fastened at one end to one of said dead-eyes, as shown at x, Fig. 1, and left free at the other end, y, to be manipulated as desired, and then made fast or 100 secure to any suitable fixture of the ship's deck or to the dead-eye, it is plain that by properly

pulling upon or letting out the rope H, first having unfastened its end y, the ship's rigging may be set up as desired, and the rope then being made fast or secure, the rigging, when 5 so set up, will be held against accidental movement or change.

I am aware that a sheave-block has heretofore been composed of sheaves journaled to rotate in a forked block; and I am also aware 10 that wooden dead-eyes, supported in metallic encircling-straps, have been constructed with transverse rounded perforations, through which the lanyards pass. Such constructions, however, do not constitute my invention, and 15 are hereby disclaimed.

Having thus described my invention, what I claim, and desire to secure by Letters Patent, is—

A dead-eye constructed in itself, with a series of external and peripheral grooves, a, to 20 receive and keep separate the parts of the lanyard, in combination with ear-pieces C, which are a part of the dead-eye, and project beyond the periphery, and are otherwise constructed for the dead-eye to be sustained in 25 operating position for the setting-up rope or lanyard, substantially as described, for the purpose specified.

In testimony whereof I have hereunto set my hand in the presence of two subscribing witnesses. 30

S. B. LUCE.
